UNITED STATES PATENT OFFICE.

HAROLD EDENBOROUGH, OF SNARESBROOK, ENGLAND, ASSIGNOR OF ONE-HALF TO G. H. PRICE AND CO., OF LONDON, ENGLAND, A FIRM.

WHEEL FOR VEHICLES.

SPECIFICATION forming part of Letters Patent No. 695,805, dated March 18, 1902.

Application filed August 21, 1901. Serial No. 72,765. (No model.)

To all whom it may concern:

Be it known that I, HAROLD EDENBOROUGH, engineer, a subject of the King of Great Britain, residing at Martham House, Snaresbrook, 5 in the county of Essex, England, have invented new and useful Improvements in Wheels for Vehicles, of which the following is a specification.

My invention relates to the wooden wheels 10 of field-guns, wagons, carts, and other vehicles, and has for its object to enable the wheel to be readily tightened up when the fellies and spokes become loose in consequence of shrinkage of the wood.

15 Reference is to be had to the accompanying drawings, forming part of this specification, wherein I have illustrated the preferred construction of rim and tire.

Figure 1 is a face view of a segment of the 20 wheel-rim, tire, and tightening device. Fig. 2 is a cross-section, and Fig. 3 is a part edge view of the same.

The same letters of reference indicate the same parts in all the figures.

25 *a* is the wooden rim of the wheel, built up of fellies, as usual, and made of double conical form on the exterior circumference, the two coned surfaces *b b* being preferably symmetrical. Without in any way confining myself

30 to a particular angle, it may be mentioned that the preferred angle of conicity is substantially as shown—namely, about forty degrees to the axis of the wheel—but it may be greater or less.

35 Between the outer tire-band *h*, forming the head of the wheel, and the wooden rim *a* are interposed two similar opposed series of segmental wedges *c c*, oppositely coned on their internal circumferences to correspond to the

40 cones *b b* of the wheel-rim, the two series of wedges *c c* being applied upon the wheel-rim from opposite sides and tightly connected by transverse bolts *d*, a sufficient interval separating the two series *c c* to allow of their being drawn closer together in order to tighten

45 up the wheel when required in consequence of the shrinking of the wood. The screw-bolts *d* are preferably shouldered, as at *e*, and have squared ends *f* for the application of a

50 spanner, the shouldered ends being received in countersunk holes *g* in the one wedge *c*,

the shanks of the bolts passing through clearance-holes in that wedge and their threaded ends screwing into corresponding holes tapped in the opposite wedge *c*, notches *i* being made in the wheel-rim *a* to give passage to the bolts. The outer band *h*, besides covering the gap between the series of wedges *c c* at opposite sides, affords the necessary abutment to enable said wedges to exert the required wedging action between the band *h* and the rim *a* when the screw-bolts *d* are tightened up, the pressure due to the wedging action serving both to tighten up the wheel and to keep the outer tire-band *h* in place. The joints between the adjacent ends of the segments *b* should preferably be alternated with the joints of the fellies composing the rim *a*. Bolts *l* may be passed radially through the band *h* and rim *a*, the segments *b* being notched at their inner edges to clear the bolts, as shown at *m* in Fig. 3.

The spokes *k* of the wheel are tenoned into the fellies of the rim in the usual manner and are preferably shouldered to abut against the inner circumference of the rim and similarly as regards the hub.

Having now particularly described and ascertained the nature of the said invention and in what manner the same is to be performed, I declare that what I claim is—

1. A wooden wheel having its rim coned in opposite directions on the external circumference, in combination with an outer encircling tire-band forming the tread of the wheel, two opposed series of segmental wedges located between the rim and tire-band, said series of wedges being oppositely coned on their internal circumference to correspond to the double-coned circumference of the wheel-rim, and transverse bolts adapted to draw the oppositely-coned segments toward each other with a wedge-like action so as to take up slackness of the joints of the wooden part of the wheel and tighten the tire-band on the wheel, as described.

2. In a wheel, the combination of a rim having its external surface inclined from the center downwardly and outwardly and provided with transverse grooves or notches, a flat tire-band, segmental wedges arranged between the band and rim and having flat outer faces

and inclined inner faces, and transverse bolts engaging the wedges to draw them toward each other, said bolts being in the grooves or notches of the rim, as set forth.

- 5 3. In a wheel, the combination with a rim having its external surface inclined from the center downwardly and outwardly and provided with transverse grooves or notches, a flat tire-band, bolts passing through the rim
10 and band, segmental wedges arranged between the band and rim and having flat outer

faces and inclined inner faces and provided with notches at their inner edges opposite the bolts securing the band to the rim, and transverse bolts engaging the wedges to draw them together, said bolts being in the grooves or notches of the rim, as set forth. 15

HAROLD EDENBOROUGH.
